UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,101, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

The principal features of my design, which is clearly illustrated in the accompanying drawing, are the parallel stripes or members A and B, each composed of a series of minor parallel stripes, bars, or ribs, of different widths and shades or colors, the stripe A being ornamented by a series of broken or interrupted narrow ribs, *a*, and by a wider rib, *b*, having a series of dots extending longitud-

inally through its center, and the stripe B having a central rib, *d*, ornamented by three longitudinal rows of dots.

Irrespective of the colors employed, I claim—

1. The design for the stripe A, as represented.
2. The design for the whole pattern including the stripes A and B, as shown.

In testimony whereof I have signed my name to this specification in the presence of two subscribing witnesses.

FRED. WINK.

Witnesses:

WM. A. STEEL,
HUBERT HOWSON.
